CIRCUIT BREAKER MOUNTING MEANS

William M. Scott, Jr., Bryn Mawr, Pa., assignor
to I. T. E. Circuit Breaker Company, Philadelphia, Pa., a corporation of Pennsylvania

Application April 4, 1945, Serial No. 586,574

8 Claims. (Cl. 200—168)

1

My present invention relates to switch gear, and more particularly to circuit breakers arranged to be constructed for simplified manufacture and assembly from a plurality of unit assemblies.

This invention further contemplates the arrangement of a circuit breaker so that it may readily be supported from a steel panel, being electrically isolated therefrom by a plurality of insulating elements each specifically adapted to support a particular unit or assembly on the steel panel.

This circuit breaker is also so constructed that it may readily be operated in a closed steel compartment aligned with a multiplicity of other compartments in a switchboard in which the compartments are in close juxtaposition to each other.

The unit assemblies of which this circuit breaker is constructed comprise essentially (1) a stationary contact assembly including blow out means and stationary arcing horn which assembly is individually and separately secured to the steel panel through its particular insulating support; (2) an arc chute assembly which is adapted to be readily independently mounted on the circuit breaker in appropriate cooperating relation with the stationary arc chute assembly; (3) a movable contact assembly which is arranged to be supported from the steel panel by its own separate support; (4) an over-current trip assembly which is supported from the steel panel also by its own independent, individual insulating support; (5) a movable contact operating assembly comprising mechanisms enclosed in a separate housing which in turn may be readily secured as a unit to supports extending from the steel panel, and readily connected by a single pin and cotter pins to the movable contact elements; (6) a hold-in assembly in a separate housing readily secured to the contact operating assembly; and (7) a control switch assembly readily and independently secured to a portion of the support which carries the contact operating assembly.

A primary object of the invention, therefore, is the construction of a circuit breaker so arranged that it may be readily manufactured and assembled from a plurality of unit assemblies particularly adapted to be inter-engaged with each other.

Another object of the invention is the arrangement of a circuit breaker structure so that the individual elements thereof may readily be supported from a steel panel, each of the individual elements being appropriately insulated from the steel panel by individual insulating supports.

Another object of this invention is the arrangement and construction of a circuit breaker in such manner that each of the parts thereof embraced in individual unit assemblies may readily

2

be interchanged with similar unit assemblies of other circuit breakers, so that the circuit breaker construction as a whole is peculiarly adapted to mass production methods and procedures.

5 Still another object of this invention is the provision of a steel supporting panel for the parts of the circuit breaker.

This steel panel mounted behind each circuit breaker and in front of the buses serves to make 10 the switchboard a "dead front" switchboard with all the attendant safety features.

A further object of this invention is the provision of novel insulating supporting elements for supporting different parts of a circuit breaker.

15 Another object of the present invention is the provision of an operating means for closing and tripping the circuit breaker.

Another object of this invention is the provision of a hold-in means for holding the circuit breaker closed against over-current conditions 20 when the circuit breaker is not intended to trip.

Another object of the present invention is the provision of a manual tripping means.

25 Another object of the present invention is the provision of a shock-absorbing means in connection with the trip unit of the circuit breaker, so arranged as to adapt a circuit breaker to appropriate sequential operation in a cascaded circuit breaker system, and to prevent the circuit breaker 30 from tripping open against unexpected physical shocks under any circumstances.

The foregoing and many other objects of the present invention will become clear from the following description and the accompanying drawings, in which:

35 Figure 1 is a view in perspective with parts of the circuit breaker removed, showing the circuit breaker of the present invention;

Figure 2 is a front view of a steel panel for supporting parts of the circuit breaker, with the parts of the circuit breaker removed therefrom;

Figure 3 is a rear view of the steel panel of Figure 2;

Figure 4 is a front view of an individual insulator member for supporting the stationary contact assembly of one pole on the stationary panel;

Figure 5 is a back view of the insulator support and assembly of Figure 4;

Figure 6 is a front view of the trip unit assembly 50 of the circuit breaker of Figure 1, showing the individual insulator support for supporting the same on the steel panel;

Figure 7 is an expanded view of the trip unit assembly of Figure 6;

Figure 8 is a view in perspective of the arc chute assembly of Figure 1.

Figure 8A is an expanded view of the arc chute assembly of the circuit breaker of Figures 1 and 8.

Figure 9 is a rear view, partly broken away, of 60 a steel cross-shelf to be secured to the front of

the steel panel for carrying the housing of the movable contact operating unit;

Figure 10 is a cross-sectional view taken on line 10—10 of Figure 9 looking in the direction of the arrows;

Figure 11 is an expanded view corresponding to that of Figure 9, showing the manner in which the supporting cross-shelf for the tripper bar of the circuit breaker is assembled;

Figure 13A is a fragmentary view in perspective of the movable contact element;

Figure 14 is an expanded view corresponding to those of Figures 9 and 11, showing the steel shelf which supports the operating mechanism, showing, however, the front of the steel shelf and the manner in which the operating mechanism, in its unit assembly, is mounted thereon;

Figure 15 is a view in perspective of the front of the steel support shelf of the circuit breaker, showing the operating mechanism secured thereon;

Figure 16 is a view in perspective of the operating mechanism for the circuit breaker with the housing thereof broken away to reveal the elements thereof;

Figure 17 is an expanded view of the elements and linkages of the operating mechanism of Figure 16;

Figure 18 is an expanded view of the hold-in and shock-absorbing unit assembly for the operating mechanism of Figures 15 and 17;

Figure 19 is a view in perspective, with a portion of the housing broken away, showing the assembled shock-absorbing and hold-in mechanisms; and

Figures 20-23 are schematic views showing successive steps in the operations of the operating mechanism of Figures 15 to 17.

Referring now to Figure 1, there is here shown the novel circuit breaker 30 of the present invention. As seen more particularly in Figure 1, the circuit breaker 30 is composed of a plurality of unit assemblies which comprise (1) a stationary contact blowout and arc horn assembly 31; (2) an arc chute assembly 33; (3) movable contact assembly 34; (4) the over-current trip unit assembly 35; (5) the operating mechanism assembly 36; (6) the hold-in and shock-absorbing assembly 37; and (7) the control switch assembly 268. The circuit breaker as shown in this figure, is a three-pole circuit breaker in which three stationary contact assemblies 31 and three arc chute assemblies 33 are provided. The movable contact assembly 34 is provided with three movable contact members as hereinafter described. An over-current trip unit assembly 35 is provided for each of the poles of the circuit breaker, the units operating a common trip bar for the operating means, as hereinafter described. A single operating assembly 36 is, however, provided, connected to the center pole of the movable contact assembly 34. Since the movable contact assemblies are mounted on a single shaft, operation of the center pole will result in simultaneous operation for the other poles. Likewise, since a single operating assembly 36 is required, only a single hold-in shock-absorbing means 37 is required.

Steel support panel

The circuit breaker 30 is supported on a steel panel 40 which is shown more specifically in Fig-

ures 2 and 3. Figure 2 shows the front of the steel panel 40, and Figure 3 shows the back thereof. Panel 40, as is readily seen in Figure 2, is of tray-like construction with a pair of horizontal flanges 41, 42 and a pair of vertical columns 43, 44 formed by bending the material of the panel rectangularly at the vertical edges into a U-channel with the corners squared. After the vertical columns 43, 44 are formed, the bending up of the horizontal flanges 41, 42 completes the tray-like structure, as seen in Figures 2 and 3. The vertical columns 43, 44 have a plurality of spaced openings 46, 48 in which are secured the spacers 47, 49. The spacers 47, as seen in Figure 3, are contained entirely within the channels or columns 43, 44 and extend rearwardly of the front face of the channels or columns. The spacers 47 furnish appropriate securing means for securing the panel 40 either to a stationary wall on or in a switchboard, or to the movable frame of a compartment.

The main body 50 of the steel panel 40 is provided with a plurality of openings 51, 52 aligned horizontally adjacent the upper end thereof, the said openings being provided to receive the back connection stud hereinafter described, for the stationary contact assemblies 31. Where the circuit breaker is constructed as a three-pole circuit breaker, then obviously, three such openings 51 will be provided.

Likewise, the lower portion of the main body 50 of panel 40 is provided with a plurality of openings 52, 52 to receive the lower back connection stud hereinafter described. Here too, in the case of a three-pole circuit breaker, three such openings 52 are provided.

The vertical columns or channels 43, 44 are provided primarily for reinforcement of the panel as a whole, and the panel is made in the form of a tray defined by the channels 43, 44 and the flanges 41, 42 in order to rigidify and strengthen the unit. The panel flanges may of course be welded together, and as shown particularly in Figure 3, it may be reinforced in any suitable manner 25 by a steel strip 54 welded or otherwise secured across the back. The steel strip 54 is shown as having a bead 55 in order to further rigidify the strain. In appropriate cases, in order to avoid magnetic effects, the strip 54 may be of stainless steel. While the strip 54 is shown across the approximate center of panel 40, it will be obvious that any appropriate number of such strips may be used as required, and spaced from each other as required.

Each pair of openings 51, 52 is connected by a slot 57, 57 in order to reduce eddy current effects in the main section 50 of the steel panel 40, which eddy current effects would serve to increase the heat generated in the panel.

In appropriate cases, non-magnetic materials may be used for panel 40, such as non-magnetic steels, aluminum sheets, magnesium sheets, and any other strong non-magnetic material.

The smaller openings shown in the main section of the steel panel 40 are for the reception of various bolts and other securing means for securing the various assemblies and their supports rigidly to the steel panel.

Another and important element of my circuit breaker construction is in the use of a steel panel 40 acting as an enclosure for the bus connections behind the steel panel, so that the switchboard becomes essentially a dead front switchboard owing to the fact that all of the circuit breakers are backed up by the steel panels. The construction of the steel panel and circuit breaker mount-

ing used in connection therewith is particularly adapted for low voltage circuit breakers, for 600 volts or below. In the past this type of breaker has been mounted on slate or ebony asbestos panels quite universally. In these designs the live parts of the breaker have been spaced on the insulating base so as to provide the proper creepage distance over the insulation. The use of a steel panel is possible only when the moldings are provided with flanges which increase the creepage distance between live parts and the steel panel which is grounded. By using flanges on the moldings it is possible to mount the live parts relatively close together and still get adequate insulation.

The use of a steel panel has been dictated by the requirement that the panel be very much lighter than it was before, particularly on ship-board, where weight is important. Steel is also stronger and not subject to breakage. It is particularly desirable where shot tests are required and breakage of insulating panels has occurred. Steel is also fireproof. Where switchboard fires have occurred in the past it has resulted in the destruction of the insulating panels. Steel also provides a grounded metal barrier between the front of the breaker and whatever is at the rear.

Stationary contact assembly and upper terminal

The stationary contact assembly as shown in Figures 1, 4 and 5 includes a back connection stud 60 which comprises a bolt secured to a terminal block 61. Current entering through the back connection stud 60 enters the blow-out coil 63, which comprises a pair of turns of a heavy low-resistance copper bar, the opposite end of the coil being connected to the terminal block 65. The heavy copper strap 66 which is substantially U-shaped in form, is connected at its lower end by the bolts 67 to the terminal 65, and at its upper end by the bolt 68 to the base of insulator 72 (hereinafter described).

Copper strap 66 has a stationary contact 70 secured thereto in any suitable manner, as by brazing and welding, and of any suitable material such as Elkenite silver. The remainder of the strap 66 above the contact 70 comprises a stationary arcing horn. Thus, while the circuit breaker is closed, the flow of current in the circuit will not be substantially affected by blow-out coil 63, owing to the low resistance thereof, and current will readily flow from the back connection stud 60, to the blow-out coil 63, to the terminal 65, to the lower end of strap 66 to the main contact 70, and thence to the movable contact. On opening the circuit breaker the current path for strap 66 will be the same, but the strap 66 will serve as a stationary arcing horn, and the blow-out coil 63 will be effective to drive the root of the arc thereon upwardly in a manner hereinafter described in connection with the arc chute assembly.

Insulating support for stationary contact assembly

As an important part of the present invention, the entire stationary contact assembly herein described from the back connection stud 60 through to the main contact 70, is mounted in the insulator tray 72.

As will be seen from Figures 4 and 5, the insulator is tray-like, or more specifically, bath-tub shaped, and is provided with a back wall 73, a pair of vertical side walls 74, 74, and a pair of horizontal walls 74, 75. The back wall 73 is secured to the main section 50 of the steel

panel 40, so that the back connection stud 60 carried by the insulator tray 72 will pass through the center of opening 51 of the main section of the panel 40.

As seen in Figure 5, the back wall 73 of the insulator tray 72 is provided with a recess 77 communicating with holes 78 through which the bolts 67 may pass to securely fasten the lower end of the copper strap and arc horn 66 to the insulating tray 72. The recess 77 is then filled with plastic insulating material.

The back wall 73 of the insulator tray 72 is also provided with a counterbored opening 80 for bolt 68, which fastens the upper end of the copper strap and arc horn 66 also to the insulating tray 72 and is provided with appropriate plastic insulating material.

Counterbored openings 82, 82 are provided in order to receive bolts which secure the terminal block of the blowout magnet to the insulator tray. After the bolts are secured in position by appropriate nuts, the counterbore of openings 82 is filled with an insulating plug in order to insulate these plugs from the steel panel.

Openings 81, 81 and 83, 83 are provided to receive bolts which secure insulator tray 72 to the steel panel. These openings 81, 81 and 83, 83 contain threaded metal inserts to receive the screws which fasten the insulator tray 72 to the steel panel.

These openings 81, 81 and 83, 83 contain threaded metal inserts to receive the screws which fasten the insulator tray 72 to the steel panel.

The back wall 73 of the insulator tray 72 is provided slightly beneath its center with a through opening 85 through which back connection stud 60 passes. The back surface of the back wall 73 of the insulator tray 72 is provided with a tubular extension 86 integral with the said back wall and surrounding the opening 85. As will be seen in Figures 1 and 5, this tubular extension surrounds the portion of the back connection stud 60 which passes through the opening 51 in the steel panel 40 (Figure 2) and prevents any flashover from the back connection stud 60 to the main section of the steel panel 40.

A plurality of laminated melamine glass strips 87 is secured in any suitable manner, as for instance by bolts 88, to the front edge of the upper horizontal wall 75 of the insulator tray 72. These laminated strips serve to limit the movement of the arc chute assembly 33 when it is mounted on the circuit breaker, and serve accurately to position the same with respect to the stationary contact assembly.

It will thus be seen that the stationary contact assembly may be assembled as a unit within the insulator tray 72, and the insulator tray may then be secured by bolts passing through openings 81, 81 and 83, 83 to the main section 50 of the steel panel with the back connection stud 60 passing through the opening 51. Accordingly, comparing Figures 2 and 5, it will be seen that the bolts passing through openings 81, 81 of the back wall of the insulator tray 72 will enter holes 90, 90 of the steel panel, and the bolts passing through openings 83, 83 will enter holes 91, 91 of the steel panel.

As a practical matter, and in order to simplify assembly, and also in order to ensure that the elements mounted within the insulator tray will be electrically isolated from the steel panel, holes 81, 81 and 83, 83 may simply be tapped metallic inserts molded therein and not extend-

ing through to the front surfaces of wall 73. An appropriate bolt may then be passed through openings 91, 91 of the steel panel 40 entering from the rear thereof to be secured in the tapped inserts in openings 81 and 83. In the specific embodiment shown in Figure 5, openings 81 and 83 are provided with such tapped metallic inserts.

Again referring to Figures 1, 4 and 5, it is seen that each unit assembly is mounted on its own individual insulated support as a separate unit; and this individual support may be readily connected to the steel panel. In the specific case of the stationary contact assembly, it will be seen that all of the stationary contact elements are mounted within the insulator tray 72 with the back connection stud 60 projecting from the rear thereof. The holes 81 and 83 are so aligned with respect to each other and with respect to the holes 85, that when the insulator tray 72 is mounted on the panel 40, then holes 90 and 81, 91 and 83 will register with each other, and hole 85 will register with hole 51. By this means, therefore, a rigid, strong steel panel may be used, while appropriate insulation for the elements of the circuit breaker is provided.

Trip unit and lower terminal

The lower back connection stud assembly and trip unit for each pole may similarly be mounted in an insulating tray, as shown at the lower portion of Figure 1 and in Figures 6 and 7.

When the circuit breaker is closed, current flows from the main stationary contact 70 to the main movable contact 95 secured to the contact lever 96 which is mounted on a contact arm 97. Current then flows from pigtail 94 which is secured in any suitable current-carrying manner to the pigtail terminal 98 (Figures 6 and 7); and then, from the terminal 98, through the heavy copper bar 99 which is given two turns to form a trip coil 100, through the said trip coil 100, to the extension 101 thereof, to the terminal block 102, then to the threaded lower back connection stud 103, which is secured to the terminal block 102 in any suitable manner.

It will thus be seen that when the circuit breaker is closed, the connection from the upper connection stud 60 to the lower back connection stud 103 is through the contacts 70 and 95 and the pigtail 94 to the trip coil 100 in series therewith. During the opening of the circuit breaker and before the arc is extinguished, the circuit is from the back connection stud 60 to the arcing horn 66, to the movable contact 95 to pigtail 94 and the trip coil 100, and the lower back connection stud 103. Thus, the trip unit shown in Figures 1, 6 and 7 is energized by the series trip coil 100.

The magnet and armature assembly of the trip unit comprises magnet 105 and armature 106. Magnet 105 is formed in the usual manner for such trip unit assemblies by a plurality of laminated iron strips secured together by the U-shaped frame members 108. Members 108 are in turn supported by the side frame members 109, 109. Members 109 are provided with flanges 110, 110, which in turn are provided with openings 111 through which bolts may be passed into openings 112 of the lower insulating tray 113 hereinafter more specifically described, to support the magnet structure.

Armature 106 is carried by the arms 115, 115, which are connected together by the yoke 116, the said arms 115 being pivoted on pin 117 passing through the aligned openings 118.

The upper horizontal leg 120 of magnet 105 is provided with the insulating tube 121 which covers the same, and which insulates coil 100 from the iron laminations of leg 120 of magnet 105. Insulating washers 122, 123 and 124 surround the tube 121 and space the turns of the coil 100 from each other. Thus the coil 100 is supported on the leg 120 of magnet 105 and is appropriately insulated therefrom.

10 The armature arms 115 are connected by the pin 126 to sleeve 127. Compression spring 128 is mounted in the sleeve 127, the upper end of the compression spring bearing against washer 129. Washer 129 has an adjusting screw 130 inserted in the surface thereof, the head of said adjusting screw 130 projecting through slot 131 of sleeve 127. The lower end of compression spring 128 bears against the base of the sleeve 127. The base of sleeve 127 is juxtaposed to the extension 133 of the sucker disk 135 of the dashpot 134. Dashpot 134 is closed by the cover plate 136 secured thereto by the bolts 137, and by the additional cover plate 138 secured over the cover plate 136.

25 The bolts 137 extend upwardly through the plates 136 and 138 to engage the horizontal flanges 140 of the supporting members 109 and thereby to secure the dashpot 134 to the assembly. Dashpot 134 is also supported on the bracket 141 carried by the extension 142 which in turn is carried between the plates 109.

30 The front of each of the members 109 is provided with a bent-over lug 143 to furnish a support for the adjusting screw housing 144, the housing being secured to the lugs 143 by bolts 145 passing through aligned openings 146, 147.

35 Housing 144 carries a vertical screw 148 rotatably mounted in the horizontal walls 149 thereof, so that it may rotate freely with respect thereto while being restrained against axial movement. Screw 148 is provided with a nut 150, a portion of which extends out through the slot 151 of housing 144, so that the nut may not rotate with the screw 148, but may move longitudinally with respect thereto when the screw 148 rotates. The lower end of screw 148 is provided with a knurled knob 152 which may be manually rotated by rotating the screw.

40 The face of housing 144 may be provided with 50 the calibrated scale 153 adjacent the slot 151, so that the nut moving up and down in the slot 151 will act as an indicator against the scale for indicating the condition of compression spring 128.

55 Nut 150 extends inwardly to engage the top surface of screw 130 secured to washer 129. Accordingly, when the knurled knob 152 is rotated to rotate the screw 148 to move the nut 150 downwardly, washer 129 will be moved downwardly 60 further to compress the spring 128. Likewise, upward movement of nut 150 will relax the spring 128 to a degree dependent upon the amount of upward movement.

65 This will vary the force of spring 128. The spring 128 is thus calibrated to determine the force on the armature which will free it of the dashpot. For currents below a predetermined value the spring will act as a rigid connection between the armature and dashpot. Above that value the spring will be compressed and the armature may move independently and instantaneously, free of the dashpot.

70 The armature 106 is further biased toward the open position by the calibrating springs 175 which are attached to the side arms 115 of the

armature 106 at one end and at the other end to the adjustable nut 150 of the calibrating screw 148.

Accordingly, the amount of magnetic attraction required to attract the armature 106 independently of the dashpot is predetermined by compression of spring 128, and this may be expressed in appropriate units on scale 153.

Each of the armature-carrying arms 115, 115 is provided with an extension 170 carrying yoke 171 therebetween, and adjustable screw 172 extends through a tapped opening in the opening 71 and is held in position by the nut 173 acting through the spring washer 174. The upper end of the adjustable screw 172 operates the tripper bar hereinafter described, said tripper bar having a lever extending in the path of each of the screws 172 of each of the trip units.

Insulating support for trip unit and lower terminal

It will be seen from Figures 1, 6 and 7, that all of the units herein described are supported in the insulating tray 113 which has substantially the shape of insulating tray 72. The insulating tray 113 has a pair of vertical side walls 155 and 156, a top wall 157 and back wall 158. The terminal block 102 is appropriately supported and positioned in the recess 160 of the back wall 158, and the back connection stud 103 extends through opening 161 in the recess. The said opening 161 is surrounded by the tubular rearward extension 162 which prevents flashover from the back connection stud 103 to the steel panel 40; i. e., when the tray 113 carrying all of the elements shown in Figures 1 and 6 is secured to the steel panel of Figure 2, the back connection stud 103 is aligned with the opening 52 to pass therethrough, and the tubular extension 162 prevents flashover from stud 103 to the material defining opening 52.

Openings in the back wall 158 of tray 113 (the said openings corresponding to openings 81, 81 and 83, 83 of tray 72) register with openings 166 of the panel of Figure 2, and similar openings at the lower end of the back wall 158 register with openings 168 of the panel of Figure 2 to secure the insulated tray 113 to the panel. It will thus be seen, particularly from Figure 6, that the entire trip assembly is secured on the tray 113, and from Figure 1, that the assembly thus secured may readily be mounted as a unit on the steel panel.

A trip unit assembly is provided individual to each of the poles so that the circuit breaker may be tripped on an overcurrent condition occurring in any of the poles, and each of these trip unit assemblies is mounted on its own tray 113 and may be secured as a unit to the panel.

Simplified assembly of circuit breaker

It will thus be seen that thus far in the process of manufacture and assembly of the circuit breaker, each stationary contact assembly is assembled as a unit on its tray 72, and each trip unit and lower back connection stud assembly is assembled as a unit on its tray 113.

In the final assembly of the three-pole circuit breaker in accordance with the novel design herein set forth, the assembler need merely select three stationary contact assemblies and secure each assembly to the panel by aligning elements 81, 81 and 83, 83 (Figure 5) of each stationary contact assembly, respectively, with openings 90, 90 and 91, 91 of the panel. Having secured the three stationary contact assemblies

to the panel, the assembler (or in mass production the next station) may merely select three trays 113 (Figures 6, 7) carrying three lower back connection stud and trip unit assemblies, and secure these to the panel by aligning the appropriate openings of the insulating trays 113 of each assembly with the respective openings 166 and 168 for each of the poles. Thus, in the specific embodiment shown, the securement of the three poles of the stationary contact assemblies to the panel involves the insertion of four bolts for each pole, or twelve in all; and similarly, the securement of the lower back connection stud and trip unit for the three poles also involves the insertion of four bolts for each assembly, or twelve bolts in all.

The entire circuit breaker is rigidified and strengthened by the steel panel construction. Insulation is provided only where necessary, and at the points where insulation is necessary sufficient insulation is provided. The walls of the trays also serve to prevent any deleterious flashover and to increase the creepage distance between adjacent poles.

The other unit assemblies of the circuit breaker may be secured to the panel or to supports carried by the steel panel, in as simple a manner.

Likewise, this invention contemplates extremely simplified connecting means for connecting together those unit assemblies which in the operation of the circuit breaker must be connected.

Bracket and shelf supports for unit assemblies

The remaining unit assemblies are supported from horizontal members 270 and 188 which in turn are supported from the steel panel 40 of Figures 2 and 3, by the side brackets 180, 180 (Figures 9, 11 and 14).

Brackets 180 are each provided with a vertical flange 181 bent normal thereto, to facilitate securement of the brackets 180 to the steel panel 40. Flanges 181, 181 are each provided with openings 182, 182 which register with holes 183, 183 at either side of the main section 50 of steel panel 40. Bolts passing through aligned holes 182, 183 secure the brackets 180 to the steel panel 40, with the brackets 180 extending from the front of the panel and normal thereto.

The brackets 180 are rigidified by making the flanges 181 continuous with the upper horizontal flanges 184 to provide a partial tray-like formation which strengthens the brackets. Also, brackets 180 are provided with downwardly extending legs 185, 185 at their rear ends so that flanges 181 may appreciably be lengthened to increase the supporting base for brackets 180.

Each of the brackets 180 is provided at its lower end with a flange 187 to which is secured the shelf 188, the same being held in rigid engagement therewith in any suitable manner. The cross-shelf 188 is preferably of steel in order to provide rigid support, but is provided with an insulating cover plate 190 secured thereover in any suitable manner.

The side brackets 180, which as above described, are normal to the main panel 40, serve not only to support the shelf 188 which in turn supports the operating mechanism, but also serve to rotatably support the movable contact assembly 34.

Movable contact assembly

The movable contact assembly, as seen in Figures 12, 13 and 13a, comprises a square steel shaft 192 covered with a suitable phenolic insu-

lation 193, each of the ends of the shaft being provided with an opening 194 parallel to the axis thereof, the said opening receiving and supporting pin 195 which is biased outwardly by the compression spring 196 captured between the base of opening 194 and the base of pin 195.

Pin 195 is limited in its outward movement with respect to opening 194 by the stop member 197 inserted through the side opening 198 which communicates with opening 194. The inner end 10 of the stop member 197 enters the groove 199 in the surface of pin 195; the pressure of spring 196 is effective only to move the pin 195 out of the opening up to the point where the base of groove 199 engages the stop 197.

Each pin 195 has an axial extension 200 of lesser diameter, which extension 200 enters the opening 201 in the circular steel bushings 202 pressed into the side brackets 180. These bushings 202 are used in order to provide sufficient hardened bearing surfaces in which the extensions 200 of the steel shaft 192 may rotate. Accordingly, the shaft 192 is rotatably supported by the pins 195 and their respective extensions 200 entering into the respective opposite openings 201 of the side brackets 180. Bushings 202 are provided with the circular flange 203 to assure their proper alignment and to properly position them in the side brackets 180.

The contact shaft 192 has mounted thereon a plurality of large-size disks 205 of insulating material for spacing the individual contact poles from each other, there being four such disks 205 mounted on the shaft 192, where, as in Figure 12, the contact shaft 192 is to support three contact assemblies for a three-pole circuit breaker—the four insulating disks 205 providing three spaces therebetween.

The two central insulating disks 205 enter into the two spaces between the side walls 155 of the insulating trays 113 to further provide interphase barriers between the three contact poles. The two outside disks 205 of shaft 192 provide an appropriate insulating barrier between the two outside movable contact poles and the steel brackets 180.

Each of the individual movable contact poles mounted on the contact shaft 192 comprises a contact-carrying arm 97 having a squared recess 210 which embraces three sides of the shaft 192. The channel-shaped steel clamping plate 211 is fitted into the recess 210 to provide a smooth bearing surface between the contact arm 97 and the shaft 192. A clamping plate 215 is engaged against shaft 192 on the fourth side thereof, and bolts 216, 217 are respectively passed through aligned openings 218—219 and 220—221 in the clamping plate 215 and the contact arm 97, and are held in place by the nuts 222, 223 to clamp the contact arm 97 on the shaft 192.

As seen more particularly in Figure 12, the contact arm 97 is formed by a pair of parallel plates 225, 226 connected by the yokes 227, 228, 229. The openings 219 and 221 for receiving the bolts from the clamping plate are located respectively in the yokes 228, 227, and the recess 210 which embraces the shaft 192 is between the yokes 228 and 227. It will thus be seen that when each of the contact arms 97 for the three poles is thus secured to the shaft 192, any rotation of shaft 192 will result in corresponding rotation of contact arms 97, owing to the fact that contact arms 97 are integrated therewith.

The yoke 229 of each contact arm 97 has an extension 230, which extension is used as a base

for the individual biasing means for contact lever 96. Contact lever 96, which carries the main movable contact element 95, is provided with a through opening 232. The plates 225 and 226 comprising contact arm 97 are at their upper ends provided with aligned openings 233. Contact lever 96 is mounted between plates 225, 226 so that the opening 232 thereof is axially aligned with openings 233 of the contact arm 97, and the pin 235 is passed through the openings 233 and 232. A set screw 236 threaded into the tapped opening 237 of the contact lever 96 is, after the contact lever 96 is mounted in place with the pin 235 in place, rotated inwardly so that the point thereof engages the annular notch 238 of the pin 235 to hold the pin in position. The contact lever 96 is by this means rotatably mounted on contact arm 97 while it is nevertheless secured thereto and movable therewith.

Contact lever 96 is also provided with a through pin 240 mounted between the side flanges thereof on which is rotatably mounted the head of the bolt 241. Compression spring 242 surrounds the bolt 241 and bears against the surface of the head thereof. The bolt 241 passes through the opening 242a of the extension 230 of contact arm 97, and the opposite end of the compression spring bears against the back surface of the extension 230. The threaded end of bolt 241 is provided with a nut 243 which limits the degree of movement imparted to the contact lever 96 around the pin 235 by the compression spring 242.

Contact shaft 192 and contact arm 97, and the lever 96 and compression spring 242, are so arranged that the contact 95 will engage the stationary contact member 70 before the contact shaft 192 has completed its closing stroke. After such engagement, further rotation of contact shaft 192 in the closing direction will result in clockwise rotation (with respect to Figure 1) of the contact lever 96 around the pin 235. The compression of spring 242 provides adequate contact pressure between contacts 70 and 95.

Pigtails 94, one for each pole, are connected by means of the screws 250 to the contact levers 96 and at their opposite ends, as previously described, are connected to the extension 98 of the trip coil 100, which in turn is connected to the terminal block 102 and the back connection stud 103.

Each of the ends of contact shaft 192 is provided with a lever 252 having a square opening 253 and a pair of small extensions 254, 254. The openings 253 are mounted over the ends of shaft 192, and the bolt 256 on each lever connecting the extensions 254 is tightened, clamping the square opening 253 around the end of shaft 192. By this means shaft 192 and the levers 252 are integrated to operate as a single unit.

Circuit breaker opening tension is provided by the tension spring 257 (Figure 1) connected at one end in the opening 258 defined by lug 259 of lever 252 (see Figures 1 and 12), and at the opposite end to a stationary pin or lug 255, 255 on the downwardly extending legs 185, 185 of the brackets 180, 180.

As seen in Figure 1, the contact shaft 192 is thereby always subjected to bias toward rotation in a clockwise direction, or a direction for opening contacts 70 and 95. This rotation is resisted when the contacts are closed by the latch means in the operating assembly herein-75 after described, which latch means in turn may

be released by operation of the trip unit to raise the bolt 172 of Figure 6 to tripping position, also as hereinafter described.

The extensions of levers 252 may also be utilized to operate various control mechanisms in response either to the opening or closing of the circuit breaker. Thus, as shown in Figure 1, one of the extensions 252 may have secured to the end thereof a link 262 pivotally held in position by pin 263 passing through an opening in the end of link 262 and a corresponding opening 264 in the end of extension 252; the lower end of the link 262 being connected by the pin 265 to the crank arm 266 which in turn is secured to the shaft 267 of a control switch 268.

Opening of the circuit breaker by clockwise rotation of shaft 192 will result in driving down link 262 to rotate the crank 266 and shaft 267 of control mechanism 268 in the counterclockwise direction to operate control mechanism 268 in an appropriate manner. Likewise, rotation of shaft 192 in a counterclockwise direction to close the contacts, will result in clockwise rotation of crank 266 and shaft 267, again to operate the control mechanism 268. Control mechanism 268 may be connected to suitable devices which are to be energized or deenergized on opening or closing movements of the circuit breaker contacts.

It will thus be seen that the movable contact assembly of Figures 12 and 13 may readily be mounted in position on the circuit breaker with a minimum of connecting operations being required by the final assembler. After the upper stationary contact assemblies are mounted in position and the lower back connection stud and trip unit assemblies are also mounted in position, the assembler need merely take the completed movable contact assembly 34, push in the pins 195 on either side against the compression of springs 196, slip the contact assembly between the brackets 180 until the pins 195 are aligned with the openings 201 of the bushings 202, whereupon the ends 200 of pins 195 will snap into openings 201 and the contact assembly 34 will be mounted in position on the circuit breaker. Removal of the contact assembly 34 is accomplished merely by pushing back the pins 195 so that the ends 200 thereof clear the openings 201 of the side brackets 180.

After the contact assembly 34 is in position, it is only necessary to connect up the springs 257 in order to provide opening tension and to connect the crank arm 310 of the movable contact assembly to link 311 of the operating assembly 36 by means of pin 312 held in place by suitable cotter pins (Figure 1). Where a control mechanism such as the control mechanism 268 is used, it is then only necessary to connect link 262 to pin 263, and by these simple operations performed by even an unskilled assembler, the entire movable contact assembly 34 is mounted in place.

The only remaining operation is to connect the pigtail 94 to the terminal 98 of trip coil 100, which again is a simple operation.

Thus the mounting of the entire movable contact assembly 34 in position on the circuit breaker, comprises the steps of snapping the resiliently mounted pins on the end thereof and openings in the side brackets, inserting pin 312 to connect the operating mechanism and crank 310, inserting pin 263 to connect the link 262 of the control mechanism 268, and attaching the end of tension spring 257 on each side.

Crank 310, which is utilized to rotate the contact shaft 192 against the bias of spring 257, is provided only at the center pole of shaft 192, since the single operating mechanism 36 need operate only in front of the one pole, the other poles all being connected by the single shaft 192. The crank 310 as shown in Figures 12 and 13, is simply a modification of the clamping plate 215, i. e., clamping plates 215 for securing the contact arms 97 are used on the two outside poles, while crank 310 acts as a clamping plate for the center pole, and connects the contact arm 97 at the center pole in exactly the same manner as does the clamping plate 215. The only difference between crank 310 and clamping plate 215 is that crank 310 has a pair of extensions 314 with aligned openings 315, the said extensions 314 comprising the crank element.

The aligned openings 315 receive pin 312 which secures the link 311 of the operating mechanism 36 to the crank 310, so that movement of link 311 in response to operation of the operating mechanism 36 results in corresponding movement of the contact shaft 192 and corresponding closing movement of the contacts.

Arc chute assembly

The arc chute assemblies 33, one for each pole, are also supported in position with respect to the stationary contact assembly (Figures 1, 8 and 8a) by a cross-bar 270 mounted across the front ends of the flanges 184, 185 of the brackets 180 and secured thereto by suitable bolts 271. Cross-bar 270 may be of metallic material, but as shown in Figure 1, is faced with a strip 272 of insulating material.

The individual arc chute assemblies 33 may more readily be seen in the perspective view of Figure 8 and the expanded view of Figure 8a. Each arc chute assembly comprises a pair of side plates 280 and a plurality of arc barrier plates 281, 281, plates 280 and 281 being of insulating material and being arranged so that they are parallel to the arc when it is drawn.

The arrangement of the arc chute plates herein shown corresponds generally to the arc chute arrangement previously described in Patent No. 2,338,715 assigned to the assignee of the present invention. However, the specific arc chute plates 281 herein are formed in a somewhat different manner owing to the fact that the circuit breaker herein shown is a smaller one. Each of the side plates 280 is provided with a pair of plates 282, 282 which are secured to the outer sides of the side plates 280, said plates 282 being of magnetizable material, preferably soft iron. Each of the side plates 280 also is provided with a recess 283 aligned with the section of the soft iron plates having the slot 284.

When the arc chute assembly 33 is mounted in position on its particular pole, the recesses 283 of the opposite side plates 280 embrace the ends of the iron core 286 of the blowout coil 63, which ends project on opposite sides from the blowout coil 63. The dimensions of the arc chute assembly 33 and of the coil 63 and its iron core 286 are such that when the arc chute assembly is in position on the stationary contact assembly, the opposite ends of the core 286 extend into the openings or recesses 283 of the side plates 280 up to the soft iron plates 282, and preferably are actually in contact with the portions of the soft iron plates 282 in which the slots 284 are located.

Accordingly, the pairs of opposite soft iron plates 282 on each of the insulating side plates

280, and the iron core 286 of the blowout coil 63, form a U-shaped magnet embracing an arc chute assembly and surrounding the path of the arc, the said magnet being energized by blowout coil 63.

Slot 284 is provided to reduce eddy currents and restrict the temperature rise especially while the circuit breaker is closed and carrying normal loads. When the contact 95 moves away from stationary contact 70, an arc is drawn therebetween. The blowout coil 63 energizing the blowout magnet 282—286—282 drives the arc upwardly, the arc acting as a half-turn current loop in the magnetic field. As the arc is driven upwardly it is squeezed into slots between the plates 281, which plates are parallel to the arc. Ordinarily, the arc is squeezed into but one of the slots, although it may be divided into a plurality of parallel arcs in two or more of the slots.

Back pressure of the arc gasses is relieved by a plurality of openings 288 in the arc chute insulating plates 281 and the arc gasses may escape through the slots between the plates 281, which slots are open at the top.

The arc chute 33 is supported at the upper rear portion thereof by the upward extensions 306 of the spacers 300. Extensions 306 are held in place by laminated melamine glass strips 87 which prevent the arc chute 33 from moving out of the recess in the insulating tray 72. The lower back edges 287 of the side plates 280 bear against the back wall 73 of the insulating tray 72 to support the arc chute 33 in an upright position. The angular recess 285 in the lower front edge of the side plates 280 cooperates with the cross-bar 270 and prevents the arc chute 33 from falling out or being accidentally dislodged due to shock.

The arc chute assembly comprising the side plates 280 and the arc barrier plates 281 as well as the iron plates 282, is secured together by a plurality of bolts 290 at the front of the chute, and 291, 292 at the back of the chute. Bolts 290 pass through aligned openings 293 in the side plates 280 and insulating plates 281 to secure the plates together at the front of the arc chute. The plates 281, 281 and 280 are spaced from each other at the bolts 290 by pairs of insulating bushings 294, 294.

Bolt 291 passes through aligned openings 295 at the upper end of the back of plates 281, 281, 280; and bolt 292 passes through aligned openings 296 at the back of side plates 280 and openings 297 at the lower end of the back of insulator plates 281. Bolts 291 and 292 also pass through openings 298 and 299, respectively, in the pairs of insulating spacers 300 at the back of the arc chute.

The lower ends of the insulator spacers 300 rest on the upper surface 301 of the arc horn 66 and thus serve further to support the arc chute in position.

When the arc chute assembly 33 is in position, the arc horn 66 and especially the upper surface 301 thereof, extends into the assembly substantially along the curved line 303 defining the bottom end of each of the insulating spacer plates 281. The arc is thus drawn at first between contacts 70 and 95; the blowout above described drives the root of the arc on one side up on the arc horn 66, and on the movable contact side drives the arc off the contact element 95 onto horn 305 of the contact lever 96, and drives the center of the arc up into the spaces between the arc chute plates, where the arc is extinguished.

Here again it will be noted that arc chute assembly 33 is easily mounted and removed as a unit

assembly on the circuit breaker, and no special connections are required.

Operating mechanism

5 The operating mechanism 36 is enclosed in a housing 320 (Figures 1, 14 and 15) having a pair of side walls 321, 322, a top wall 323, and a front wall 324. Side walls 321, 322 have horizontal flanges 325, 325, which rest on the shelf 188 and which are secured thereto by suitable bolts passing through aligned openings in the flanges 325 and the shelf 188. The entire operating mechanism is enclosed in the housing 320 to form an operating assembly 36 which, as may be readily seen from Figures 14 and 15, may be mounted as a single unit assembly on the circuit breaker.

An insulating cover member 327 of impregnated fibrous material having a top section 328 and an oblique section 329 is secured to the top wall 323 of the housing 320 by bolts 330 passing through aligned openings therein. The oblique section 329 registers with the back ends of the side walls 321, 322, and covers the back of the housing 320. Section 329 of the insulating cover sheet 327 is provided with an opening 332 through which the link 311 of the operating mechanism passes to engage the crank 310 of the movable contact assembly 34.

The operating mechanism as shown in Figures 30 16 and 17 and the schematic views of Figures 20 to 23, comprises an operating link 350 rotatably mounted on the cross-pin 351 carried by the side walls 321, 322. Operating link 350 has a front extension 352 carrying the roller 353 and a back extension 354 which coacts with the pin 355 of link 356. When the operating link 350 is rotated in a clockwise direction with respect to Figure 16, the operating lever 354 is raised to bear upwardly against the surface of pin 355 on link 356 and raises the pin 355.

Link 356 is formed by a pair of arms 360, 360 connected by a yoke 361, the ends of arms 360 opposite pin 355 being rotatably mounted on the cross-pin 400. Accordingly, when the pin 355 is raised by clockwise rotation of the operating link 350, the link 356 is also rotated in a clockwise direction around the pin 400.

Pin 355 carries rotatably mounted thereon the link 311 which is connected to the crank 310 and movable contact operating mechanism 34.

The means for rotating the operating link 350 comprises the rotatable shaft 363 which is rotatably mounted in bearings 364, 365 which extend from a base plate 366 secured in any suitable manner to the flanges 325 of the housing, the said shaft 363 being keyed to and rotating the cylinder 367 which rotates between the bearings 364, 365.

60 Cylinder 367 is provided with a cam 368 on which the roller 353 rests. Roller 353 is accordingly a cam follower. Rotation of shaft 363 in a clockwise direction rotates the cylinder 367 and cam 368 also in a clockwise direction to drive the roller 353 away from the front wall 324 of the housing 320 toward the rear thereof. This results in clockwise rotation of the operating link 350 around the pin 351, and in consequence raises the extension 354 thereof to bear upwardly against pin 355 and accordingly to rotate the link 350 in a clockwise direction also around the pin 351.

When the link 356 is thus raised from the lower position shown in Figure 16 to the upper position, it drives the free end of connecting link 311 forward to rotate the crank 310 of the movable con-

tact assembly in a counterclockwise direction and thus to close the contacts.

Pin 355 carries a roller 370 which, of course, rises with the pin 355. At the completion of the closing movement of the operating mechanism, roller 370 rides up onto the top end of the abutment 372.

Abutment 372 is an extension of the sleeve 373, which sleeve is rotatably mounted on the pin 374 which in turn is also carried between the side walls 321 and 322. Sleeve 373 has a lower extension 375, which extension is embraced by one end 376 of the coil spring 377, the opposite end 378 of the coil spring 377 engaging the cross-pin 380 which also is mounted between the side walls 321, 322 of the housing. Coil spring 377 thus biases the sleeve 373 and the abutment 372 towards rotation in a clockwise direction with respect to Figure 17 around the pin 374.

In the open position of the circuit breaker, the rotation of the abutment 372 in a clockwise direction is limited by the fact that the lower extension 375 of sleeve 373 also engages pin 380.

As the pin 355 is raised, the roller 370 carried thereby bears against the front surface 381 of the abutment 372, and rotates said sleeve 373 and its shaft 363 and extension 375 in counterclockwise direction against the bias of spring 377, moving the abutment out of the way to permit the roller 370 to rise until the roller clears the top of the abutment. At this time the spring 377 rotates the abutment 372 clockwise once more to its original position, at which position the extension 375 thereof engages the pin 380 once more, and further rotation of the abutment 372 clockwise in response to the bias of spring 377 is limited. The abutment 372 is brought to the specific position best shown in Figure 17 where it supports the roller 370.

At this time, therefore, on completion of the closing movement of the circuit breaker, the link 356 and link 311 which are in toggle relation with respect to each other, have their knee pin 355 supported by abutment 372.

Accordingly the operating link 350 is no longer required to support the pin 355. The operating link is thus provided with a tension spring 385 connected at one end to the pin 386 on the side wall of the housing, and connected at the other end to pin 387 on the operating link 350, which pin is located at a point eccentric to the mounting pin 351; this spring biases operating link 350 toward rotation in counterclockwise direction. When the rotative force on shaft 363 is accordingly released after closing of the circuit breaker, the tension spring 385 will return the operating link 350 to the position shown in Figure 16. The shaft 363 will also be returned to its original position, since the bias on the operating link 350 which rotates it in a counterclockwise direction is transmitted through the roller 353 to the cam 368, which therefore rotates the cylinder 367 and shaft 363 back to the original position.

The specific circuit breaker operator shown comprises the handle 390 which has a rectangular opening which may be readily secured over the milled extension 391 of the shaft 363 (Figure 16) and may be integrated therewith in any suitable manner, as for instance by appropriate bolts passing through opening 392 of the milled extension 391 and the handle.

Since the cylinder 367 rotates in the bearings 364, 365, no further support for the cylinder is required. Accordingly, the milled extension 391 of the shaft 363 need not be rotatively carried in

the front panel of the compartment. Instead, the escutcheon plate for the circuit breaker need be supported only from the shelf carried between the brackets, which in turn are supported by the steel panel carrying the entire circuit breaker. Therefore, simply on removal of the handle 390 the front panel of the compartment may be removed or the panel door may be swung open. This ensures a dead-front operation of the switchboard, since the front panel or front door is not operatively connected in any way to the circuit breaker itself. This is so because this type of construction eliminates the necessity for fastening anything to the front of the switchboard door. By making the opening in the switchboard door or panel sufficiently large, some interchangeability can be achieved by having the operating handle come out at different places for different type circuit breakers.

Link 356 is rotatably mounted on pin 400. Pin 400 during closing is normally stationary. However, during the tripping operation the pin 400 is so arranged that it will move to the right with respect to Figures 16 and 17. Since the roller 370 is mounted on pin 355 carried on the opposite end of link 356, the roller 370 will thus be pulled off the abutment 372 and thus permit the opening tension of spring 257 of the movable contact assembly 34 to drive the link 311 to the right and thus collapse the operating mechanism.

Cross-pin 400 is mounted on the trip arm 402. Trip arm 402 as seen in Figures 16 and 17, has a yoke 403 connected thereto, the opposite end of the yoke carrying the short arm 404. The tripping arm 402 is rotatably mounted on the pin 351 which passes through the upper end of arm 402 and 404.

During the tripping of the circuit breaker, the trip arm 402 rotates in a clockwise direction around the pin 351, thus pulling the pin 400 mounted between elements 404 and 402 toward the right to cause collapse of the operating mechanism in the manner above described.

The lower end of trip arm 402 is provided with a latch tip 405 engaging the milled shaft 406. Latch tip 405 registers with that portion of the shaft 406 having the milled groove 407, the said groove being milled through to a distance slightly beyond center.

In the normal operation of the circuit breaker with the circuit breaker elements closed as shown in Figure 17, the milled shaft 406 will resist any rotation of the latch tip 405 to the left, or in clockwise direction. Milled shaft 406 is so arranged, however, that on occurrence of a predetermined overload condition, it will be rotated clockwise in a direction to rotate the milled section 407 opposite the latch tip 405, so that the latch tip 405 will permit rotation of the trip arm 402 and thus will permit collapse of the operating mechanism.

Thus, in the closed position of the circuit breaker, the abutment 370 is supported at the end of the toggle comprising link 356 as one of the toggle elements, with the pin 400 forming the knee pin, and the portion of arm 404 between pin 400 and pin 351 acting as the other link of the toggle.

The knee pin 400 of this toggle is slightly above center so that the toggle may permit counterclockwise rotation of the portion of arm 404 between pins 400 and 351 to pull link 356 to the right to pull the roller 370 off the abutment.

Thus, on rotation of milled shaft 406 in a clockwise direction, the latch tip 405 is moved into the milled portion 407 in the milled shaft 406 by

opening tension of the opening spring 257 transmitted thereto through link 311, link 356, and then to pin 400 mounted on the latching arm 402.

In order to return the latching arm 402 to its original latching position after tripping of the circuit breaker, a tension spring 401 is mounted between the pin 400 and the cross-pin 374 on the far side of the operating mechanism (with respect to Figure 16 and Figure 17). This tension spring is not sufficiently strong to counteract the opening tension of spring 257, but when the circuit breaker is completely open and the latch arm 402 is no longer subject to the opening tension thereof, this last-mentioned spring is sufficient to return the trip arm 402 to its original latch position, where it may engage the milled shaft 406.

The latch arm 402 also has an extension 410 on the opposite side of the milled shaft 406 from the latching tip 405 to prevent the latch arm 402 from being rotated counterclockwise about the pin 351 away from the milled shaft 406 during the resetting operation.

Accordingly, the moment the trip movement of the circuit breaker is completed, the elements are all re-latched so that the circuit breaker may be promptly closed.

Milled shaft 402 is operated to tripping position by the tripping unit previously described in connection with Figures 6 and 7. The bolt 172 on the armature 170 acts as the striking member to rotate the trip shaft 412 (Figure 9) rotatably mounted on the downwardly extending flange 413 of the insulating cover 190 and of shelf 188. The trip shaft 412 has a plurality of extensions 414, 414, one for each pole, each of which may be struck by striking the member or bolt 172 for that pole, and an additional downwardly extending extension 415 to limit counterclockwise rotation (with respect to Figure 10) of the trip bar 412.

The trip bar 412 is held in position by clamping blocks 417 secured in any suitable manner to the downward extension 413 of shelf 188, and clamping plates 418, 418 secured over the recessed portions 419, 419 of shaft 412, which recessed portions are received in the recesses 420, 420 of the clamping blocks 417.

Trip shaft 412 has additional extensions 421, 421 projecting through openings 422, 422 in the extension 413 of the shelf 188 and its cover 190 to balance shaft 412 and further to limit rotation thereof in either direction.

The trip shaft 412 has a crank extension 425 to the end of which is connected, by the bolt 426, a link 427 which in turn is connected to the arm 430 of a bell crank lever 431 mounted on the milled shaft 406 and keyed thereto for rotation therewith.

Consequently, any operation of any of the armatures to rotate the trip shaft 412, will result in rotation of crank 425 to drive link 426 to rotate the bell crank lever 431 clockwise with respect to Figure 17 and thus rotate milled shaft 406 in a tripping direction.

The milled shaft 406 also has connected thereto the lever 435 (Figure 1) to one end 436 of which is connected the tension spring 437 which biases the milled shaft 406 to the non-tripping position after same has been tripped. The opposite end 438 of the lever engages an adjustable stop 439 which may be adjusted accurately to regulate the angular position of the milled groove 407 of milled shaft 406 with respect to latch 405.

Shock absorber to prevent contact closing on physical shock

Since the circuit breaker herein disclosed is designed for use in connection with naval craft, which may at times be subject to severe physical shock owing to recoil or impact of gun fire or aerial bombs, various shock-absorbing means are provided both for the operating and tripping mechanisms.

Thus, weight 440 is rotatably mounted on pin 380 and is so arranged that on occurrence of physical shock caused by vibration of the structural steel of the vessel, it will rotate counterclockwise with respect to pin 380. This occurs by reason of the fact that extension 441 thereof rests against the shelf 188 and the physical shock received by the vessel is transmitted through the structural steel to the framework which supports the circuit breaker panel, through the circuit breaker panel to the brackets 180, to shelf 188, then to extension 441 and weight 440.

The physical shock herein discussed is not merely heeling or skidding of the vessel, but rather a "billiard ball" type transmission of physical shock by the transmission of a wave through the material of the vessel at a speed of the order of 15,000 feet per second in steel structures.

When the weight 440 is thus kicked up by physical shock, the extension 443 thereof strikes the pin 444 which sets the weight 445 in motion in a counterclockwise direction.

The weight 445 is rotatably mounted on pin 374, and has a lower extension 446 which on rotation of weight 445 in counterclockwise direction, moves over extension 448 of the link 356.

It will be clear that if the link 356 were to be kicked up in any way for a sufficient distance to engage roller 370 on the end of abutment 372, the circuit breaker would be closed. Consequently, the shock absorbing device driving the weight 440 and additional weight 445-446 is designed to intercept the link 356 during its movement in response to shock, to prevent closing of the circuit breaker by shock. This interception occurs as above described because a physical shock will cause the weight 445 rotated by weight 440 to move over link 356 to prevent it from rising.

The extension 446 of weight 445 will move into position above extension 448 of link 356 under physical shock before the link 356 has time to move in response to the same shock. This is so because weight 440 is free to move directly in response to physical shock. It strikes the pin 444 a hammer blow at tremendous speed, thus rotating the weight 445-446 at high speed into the path of movement of extension 448 of link 356. Link 356, however, is not as free to move as are weights 440 and 445, since the link 356 is connected to the entire operating mechanism of the circuit breaker and is subject to the tension of the heavy opening spring 257 (Figure 1). Accordingly, extension 446 of weight 445 will arrive in blocking position with respect to link 356 before said link can begin to move toward closing position.

Weight 440 is, of course, immediately restored by gravity to its original position. Tension spring 450 connected to the pin 451 of weight 445 gives it a bias toward rotation in clockwise direction to restore weight 445 to its original position where its lower extension 446 rests against pin 380, thus spacing its pin 444 from extension

443 so that the weight 445 will be struck a hammer blow.

Manual trip, hold-in and trip shock absorber assembly

In addition to automatic tripping of the circuit breaker, it may be tripped manually by the hold-in shock-absorbing and trip mechanism shown in Figures 18 and 19. The assembly 37 comprises a hold-in assembly, and also provides the shock-absorbing device to prevent accidental tripping of the circuit breaker (when it is closed in response to shock), and a device for manually tripping the circuit breaker.

The hold-in assembly 37 is contained in its own tray-like housing 335 having a side wall 336, a front wall 337 and a top wall 338, the side opposite the side wall 336 being open, so that when the assembly 33 is mounted in its appropriate position on the circuit breaker, the side wall 321 of housing 320 of the operating mechanism completes the enclosure for assembly 37 and furnishes the side wall opposite the side wall 336. The hold-in assembly 37 is secured in position against the side wall 321 of housing 320 by bolts 340 passing through openings 341 of the side wall 336 of the hold-in assembly 37 and passing laterally through the entire hold-in assembly into tapped openings 342 of side wall 321 of housing 320 of the operating assembly 36.

The housing 335 carries a shaft 460 between the front and back walls, the said shaft being squared at 461 to provide an appropriate support for the handle 462. Shaft 460 is both rotatably mounted in the front and back walls of housing 335 and longitudinally movable with respect thereto. When the handle 461-462 is rotated toward the left, the pin 464 on shaft 460 strikes the extension 430a of bell crank lever 431 to rotate the milled shaft 406 to tripping position. Tension spring 465 connected at one end to the pin 466 of the shaft 460 and at the other end to the stationary pin 467 in the housing 335, resets the shaft 460 to its initial position after release of the handle 461-462. Accordingly the circuit breaker mechanism may be tripped simply by rotation of the handle 462 in a counter-clockwise direction.

Shaft 460 and the circuit breaker trip mechanism are so arranged that pushing the shaft 460 inwardly will result in locking the circuit breaker against tripping in response either to overcurrent conditions or shock. For this purpose the milled shaft 406 is slidably mounted in its bearings between the side walls of the operating mechanism housing. It is maintained in its ordinary operating position by the leaf spring 470 secured to the extension 471 on the outside wall 322 of housing 320, the end of the milled shaft 406 extending through the side wall 322 to engage the lower end of the leaf spring 470. An adjustable stop nut 473 is provided on the side wall 322 to limit the inward movement of the leaf spring 470 so that the milled shaft will be returned to its appropriate position on relaxation of the holding force.

The opposite side of the milled shaft 406 carrying the bell crank lever 431 carries a large nut 480 secured thereto and locked in position by the lock washer 481. The large nut 480 registers with the recess 482 in the shaft 460. The recess 482 has a chamfered side wall 483.

When the shaft 460 is pushed inwardly from the front of the housing, the recess 482 is also pushed inwardly, and the nut 480 rides axially out of

recess 482 onto the chamfered wall 483. This moves the milled shaft 406 to the right by a distance sufficient to cause the milled groove 407 thereof to clear the latch tip 405 of the latch arm 402. Accordingly, the latch arm 402 cannot rotate into the milled portion 407, even though the milled shaft 406 should be rotated to tripping position.

When the shaft 460 is drawn outwardly again, the nut 480 on the end of shaft 406 may ride back into the recess 482, and the entire milled shaft is forced back to original position by leaf spring 470 so that the milled portion 407 thereof is aligned with trip arm 402.

Accordingly, an inward longitudinal push on shaft 460 will result in a hold-in of the circuit breaker, since it prevents the trip mechanism from operating either in response to physical shock or in response to overload conditions.

The shaft 460 is provided at its rear end with an opening 485 receiving a compression spring 486, and the back wall of the housing 335 is provided with a plate 487 secured in position by bolts 488, the compression spring being captured between the base of opening 485 in shaft 460 and the front surface of plate 487 having the spring centering extension 489.

Consequently, compression spring 486 biases the shaft 460 outwardly to its non-hold-in position. When the shaft 460 is pushed in to hold-in position, spring 486 is compressed, and on release of handle 462 spring 486 drives the shaft 460 back to non-hold-in position.

The housing 335 is also provided with pin 490 on the side wall 336 thereof which rotatably carries the weight 491. The weight 491 is provided with a pin 492 which registers in front of the extension 430 of lever 431. Should any physical shock of the type hereinbefore described tend to initiate rotation of the milled shaft 406, then of course, the bell crank lever 431 will also begin to rotate.

The extension 430 of bell crank lever 431 is so arranged, as to be in contact with the pin 492 of weight 491. This will strike the weight 491 a hammer blow, causing the same to rotate and will absorb the energy of the milled shaft 406. Since the weight 491 has a greater mass than shaft 406, said shaft will, on striking the pin 492, give up all its rotational energy to weight 491 and maintain its original position, while weight 491 will continue to rotate. Thus the physical shock will be absorbed, and accidental tripping on the occurrence of such shock will be prevented.

Weight 491 is biased back to its original position by tension spring 493 held at one end on pin 494 of the weight 491, and at the other end at a stationary point on the housing. Weight 491 will rotate until overcome by bias of spring 493. Weight 491 is approximately fixed in its original position by the tension spring 493. By this means, therefore, the circuit breaker operating mechanism is so arranged that it will not be accidentally tripped on occurrence of physical shock. However, when the trip mechanism operates to rotate the milled shaft, it will have sufficient continuous force (as distinguished from the momentary force of a physical shock) to push the weight along to permit the trip to occur. This may add some time delay which would, however, be useful to obtain sequential operation of circuit breakers, as described in U. S. Patent 2,439,165 issued April 6, 1948.

The circuit breaker operating mechanism is shown schematically in Figures 20-23. Figure

20 shows the closed position thereof, with link 311 pushed forward to raise the crank 310 and close the contact arm 97, and with the roller 370 on the abutment 372. The operating link 350 is shown raised to lift up the roller 370, and the latch arm 402 is shown in appropriate latching engagement with the milled shaft 406. Cam follower 353 is shown pushed forward by the cam 368 of the handle mechanism.

As above described, immediately on release of the handle, the link 350 and its cam follower 353 are pushed back while all the other elements remain as shown in Figure 22.

On the occurrence of overload conditions the milled shaft 406 is rotated to permit the latch tip 405 of the trip arm 402 to move into the milled portion 407 of milled shaft 406, as seen in Figure 21.

Then, as seen in Figure 22, the roller 370 drops off the abutment 372 to open the circuit breaker.

Thereafter, as seen in Figure 23, the latch arm 402 is restored to its initial position, and the milled shaft 406 is restored to latching position, so that the circuit breaker may again be moved from the open position of Figure 25 to the closed position of Figure 20.

In the foregoing I have described an illustrative embodiment of my invention wherein a steel panel is used for supporting the entire circuit breaker, and the live parts of the circuit breaker have been placed on insulated bases so as to provide the proper creepage distance from the insulation. I have also described the arrangement of my unit assemblies whereby various portions of the circuit breaker may be readily supported from the steel panel while being appropriately insulated therefrom, and so that the circuit breaker may be manufactured and assembled by mass production methods. Since many modifications and variations of my invention will be apparent to those skilled in the art, I prefer not to be bound by the description herein set forth but by the appended claims.

I claim:

1. A circuit breaker adapted for use with other similar circuit breakers in a dead front switchboard, said circuit breaker comprising a stationary contact element, a movable contact element, operating means for moving said movable contact element and current responsive elements for controlling said operating means; a metal panel for supporting the circuit breaker; molded insulating supporting members individual to each of said elements and carrying each of said elements as a separate unit; and means for securing each of said insulating supporting members to said metal panel; and means for interconnecting said individual elements with each other and with the operating means, said insulating members having insulating extensions to increase the creepage distance between the elements carried thereby and said metal panel; said panel, when the circuit breaker is mounted in a switch board together with other similar circuit breakers, combining with adjacent panels to form a dead front switchboard.

2. A multiple circuit breaker; each pole comprising a stationary contact element, a movable contact element, operating means for moving said movable contact element; a metal panel for supporting the circuit breaker; molded insulating supporting members individual to each of said elements and carrying each of said elements as a separate unit; and means for securing each of

said insulating supporting members to said metal panel; and means for interconnecting said individual elements with each other and with the operating means; said insulating members having insulating extensions to increase the creepage distance between the elements carried thereby and said metal panel, and acting as interpole barriers between adjacent poles.

3. A circuit breaker support comprising a metal panel; said circuit breaker having a connecting element including a back connection stud; a member of insulating material for supporting said connecting element and back connection stud on said panel; said panel having an opening; said connecting element and back connection stud being secured to one surface of said insulating member; the opposite surface of insulating member being secured to said panel; an opening through said insulating member; said opening in the insulating member registering with said opening in the panel when said insulating member is secured thereon; said back connection stud passing through the openings in said insulating member and said panel, said insulating member being substantially of tray-like formation having walls projecting from said first mentioned surface to increase the creepage distance between said connecting member and said panel.

4. A circuit breaker support comprising a metal panel; said circuit breaker having a connecting element including a back connection stud; a member of insulating material for supporting said connecting element and back connection stud on said panel; said panel having an opening; said connecting element and back connection stud being secured to one surface of said insulating member; the opposite surface of insulating member being secured to said panel; an opening through said insulating member; said opening in the insulating member registering with said opening in the panel when said insulating member is secured thereon; said back connection stud passing through the openings in said insulating member and said panel, said insulating member being substantially of tray-like formation having walls projecting from said first mentioned surface to increase the creepage distance between said connecting member and said panel.

5. In a circuit breaker supported on metal panel; means for securing an element of the circuit breaker on said panel; said means comprising an insulating member having a surface carrying said element; the opposite surface of said insulating member being secured to said panel; said insulating member having an area substantially less than that of the panel; said insulating member being substantially of tray-like formation having walls projecting from said first mentioned surface.

6. A circuit breaker comprising a movable contact element, a complementary contact element, operating means for moving said movable contact element, and a current responsive element for controlling said operating means; a metal panel; an insulating tray-like member carrying said complementary contact element; another insulating tray-like member for carrying said current responsive element; said insulating tray-like members being secured to said metal panel; brackets supported from said metal panel; said movable

contact element being mounted on said brackets; and a shelf carried by said metal panel; said operating means being carried by said shelf; means mechanically interconnecting said current responsive element and said operating means; and means electrically interconnecting said current responsive means, said movable and said complementary contact.

7. A circuit breaker comprising a movable contact element, a complementary contact element, operating means for moving said movable contact element, and a current responsive element for controlling said operating means; a metal panel; an insulating tray-like member carrying said complementary contact element; another insulating tray-like member for carrying said current responsive element; said insulating tray-like members being secured to said metal panel; brackets supported from said metal panel; said movable contact element being mounted on said brackets; and a shelf carried by said metal panel; said operating means being carried by said shelf; means mechanically interconnecting said current responsive element and said operating means; and means electrically interconnecting said current responsive means, said movable and said complementary contact, said complementary contact and said current responsive means being each connected to individual back connection members; an opening in each tray-like insulating member; and openings in said panel; the opening in each insulating member registering with an opening in said panel; said back connection members being carried by said insulating members and passing through said openings.

8. A circuit breaker comprising a movable contact element, a complementary contact element, operating means for moving said movable contact element, and a current responsive element for controlling said operating means; a metal panel; an insulating tray-like member carrying said complementary contact element; another insulating tray-like member for carrying said current responsive element; said insulating tray-

like members being secured to said metal panel; brackets supported from said metal panel; said movable contact element being mounted on said brackets; and a shelf carried by said metal panel; said operating means being carried by said shelf; means mechanically interconnecting said current responsive element and said operating means; and means electrically interconnecting said current responsive means, said movable and said complementary contact, said complementary contact and said current responsive means being each connected to individual back connection members; an opening in each tray-like insulating member; and openings in said panel; the opening in each insulating member registering with an opening in said panel; said back connection members being carried by said insulating members and passing through said openings, each insulating member having a tubular back extension around its opening surrounding the back connection member and extending through the opening in the panel.
